UNITED STATES PATENT OFFICE

FRANK J. ABEL, OF MASSAPEQUA, NEW YORK

DESIGN FOR A CLOCK CASE

Application filed June 15, 1932. Serial No. 44,088. Term of patent 14 years.

To all whom it may concern:

Be it known that I, FRANK J. ABEL, a citizen of the United States, residing at Massapequa, county of Nassau and State of New York, have invented a new, original, and ornamental Design for a Clock Case, of which the following is a specification, reference being had to the accompanying drawing, forming ing a part thereof, in which the figure is a side perspective view of a clock case showing my new design, the same being of slight depth and the opposite side unornamented.

I claim:

The ornamental design for a clock case, as shown and described.

FRANK J. ABEL.
